UNITED STATES PATENT OFFICE.

CHARLES W. SHONK, OF CHICAGO, ILLINOIS.

DESIGN FOR A SIGN.

SPECIFICATION forming part of Design No. 33,668, dated December 4, 1900.

Application filed October 20, 1900. Serial No. 33,786. Term of patent 14 years.

To all whom it may concern:

Be it known that I, CHARLES W. SHONK, a citizen of the United States, residing at Chicago, in the county of Cook and State of Illinois, have invented and produced a new and original Design for a Sign; and I hereby declare the following to be a full, clear, and exact description thereof, reference being made to the accompanying drawings, forming a part hereof.

In the drawings, Figure 1 is a view in front elevation of a sign embodying my design, and Fig. 2 a central transverse section thereof.

As shown in the drawings, the leading or material feature of my design consists of a central circular plate A, projecting forward from the circular edge of which is a marginal wall B, this wall having an inward inclination, the wall B continuing outward and backward and terminating on a line in the plane of the central plate A. As shown, the outer

part of the circular wall B has an outwardly-flaring shape, as indicated at C, changing into a plane or flattened surface, as indicated at D, and thence continuing in a backward flaring line E, where it terminates in a bead F.

The essential and material features of the design are the plate A and the inward converging wall B at the edge thereof.

Ornament the surface both of the plate A and of the sides to simulate the grain of wood or other natural material, and the sides are shown to have dividing or spacing marks G.

What I claim as new, and desire to secure by Letters Patent, is—

The design for a sign as herein shown and described.

CHARLES W. SHONK.

In presence of—

D. W. LEE,
ALBERT D. BACCI.
